(57) **CLAIM**

The ornamental design for a portable DVD, CD, and MP3 player, as shown and described.

DESCRIPTION

A portion of this patent document contains material which is subject to copyright protection. The copyright owner has no objection to the facsimile reproduction by anyone of the patent document or the patent disclosure, as it appears in the Patent and Trademark Office patent files or records, but otherwise reserves all copyrights whatsoever.

FIG. 1 is a perspective view of a portable DVD, CD, and MP3 player showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a rear elevational view thereof; and,

FIG. 7 is a front elevational view thereof.

The broken lines, which define the bounds of the claimed design form no part thereof.

The broken lines environmental are for illustrative purpose only and form no part of the claimed design.

1 Claim, 4 Drawing Sheets

FIG. 1
